CLAIM

The ornamental design for an inner cannula for tracheal tube assembly as shown and described.

DESCRIPTION

This application is concurrently filed with U.S. Design application entitled "Tracheal Tube Assembly", now U.S. patent application Ser. No. 29/871,906 filed on Mar. 1, 2023, the entire contents of which are incorporated herein by reference in its entirety.

FIG. 1 is a perspective view of an inner cannula for tracheal tube assembly according to the new design.

FIG. 2 is another perspective view thereof.

FIG. 3 is another perspective view thereof.

FIG. 4 is a front view thereof.

FIG. 5 is a rear view thereof.

FIG. 6 is a left side view thereof.

FIG. 7 is a right side view thereof.

FIG. 8 is a top plan view thereof; and,

FIG. 9 is a bottom plan view thereof.
